CODED SIGNALING RECORDER

Charles J. Manning, West Newton, Mass., assignor
to The Gamewell Company, Newton Upper
Falls, Mass., a corporation of Massachusetts

Application February 25, 1949, Serial No. 1,074

Term of patent 14 years

(Cl. D64—11)

To all whom it may concern:

Be it known that I, Charles J. Manning, a citizen of the United States, residing at West Newton, county of Middlesex, Commonwealth of Massachusetts, have invented a new, original, and ornamental Design for Coded Signaling Recorder, of which the following is a specification, reference being had to the accompanying drawing, forming a part thereof.

The figure is a perspective view showing the front, top and one end of my coded signaling recorder, the bottom, rear and end not shown being plain.

I claim:

The ornamental design for a coded signaling recorder, substantially as shown and described.

CHARLES J. MANNING.
